CLAIM

We claim the ornamental design for a binocular pack and harness set, as shown and described.

DESCRIPTION

FIG. 1 is a front, top perspective view of the binocular pack and harness set, showing our new design.

FIG. 2 is a rear, lower perspective view of the binocular pack and harness set of FIG. 1.

FIG. 3 is a front elevation view of the binocular pack and harness set of FIG. 1.

FIG. 4 is a rear elevation view of the binocular pack and harness set of FIG. 1.

FIG. 5 is a right side view of the binocular pack and harness set of FIG. 1.

FIG. 6 is a left side view of the binocular pack and harness set of FIG. 1.

FIG. 7 is a top plan view of the binocular pack and harness set of FIG. 1.

FIG. 8 is a bottom plan view of the binocular pack and harness set of FIG. 1.

FIG. 9 is a front, top perspective view of the binocular pack and harness set of FIG. 1 with compartments open.

FIG. 10 is a front, top perspective view of the binocular pack of the binocular pack and harness set of FIG. 1.

FIG. 11 is a rear, lower perspective view of a binocular pack of the binocular pack and harness set of FIG. 1.

FIG. 12 is a front elevation view of the binocular pack of the binocular pack and harness set of FIG. 1.

FIG. 13 is a rear elevation view of the binocular pack of the binocular pack and harness set of FIG. 1.

FIG. 14 is a right side view of the binocular pack of the binocular pack and harness set of FIG. 1.

FIG. 15 is a left side view of the binocular pack of the binocular pack and harness set of FIG. 1.

FIG. 16 is a top plan view of the binocular pack of the binocular pack and harness set of FIG. 1.

FIG. 17 is a bottom plan view of the binocular pack of the binocular pack and harness set of FIG. 1.

FIG. 18 is a front, top perspective view of the binocular pack of the binocular pack and harness set of FIG. 1 with a top flap in open configuration.

FIG. 19 is a rear, lower perspective view of the binocular pack of the binocular pack and harness set of FIG. 1 with the top flap in open configuration.

FIG. 20 is a front elevation view of the binocular pack of the binocular pack and harness set of FIG. 1 with the top flap in open configuration.

FIG. 21 is a rear elevation view of the binocular pack of the binocular pack and harness set of FIG. 1 with the top flap in open configuration.

FIG. 22 is a right side view of the binocular pack of the binocular pack and harness set of FIG. 1 with the top flap in open configuration.

FIG. 23 is a left side view of the binocular pack of the binocular pack and harness set of FIG. 1 with the top flap in open configuration.

FIG. 24 is a top plan view of the binocular pack of the binocular pack and harness set of FIG. 1 with the top flap in open configuration.

FIG. 25 is a bottom plan view of the binocular pack of the binocular pack and harness set of FIG. 1 with the top flap in open configuration.

FIG. 26 is a front, top perspective view of a rangefinder case of the binocular pack and harness set of FIG. 1.

FIG. 27 is a rear, lower perspective view of the rangefinder case of the binocular pack and harness set of FIG. 1.

FIG. 28 is a front elevation view of the rangefinder case of the binocular pack and harness set of FIG. 1.

FIG. 29 is a rear elevation view of the rangefinder case of the binocular pack and harness set of FIG. 1.

FIG. 30 is a right side view of the rangefinder case of the binocular pack and harness set of FIG. 1.

FIG. 31 is a left side view of the rangefinder case of the binocular pack and harness set of FIG. 1.

FIG. 32 is a top plan view of the rangefinder case of the binocular pack and harness set of FIG. 1.

FIG. 33 is a bottom plan view of the rangefinder case of the binocular pack and harness set of FIG. 1.

FIG. 34 is a front, top perspective view of the rangefinder case of the binocular pack and harness set of FIG. 1 with a top flap in open configuration.

FIG. 35 is a rear, lower perspective view of the rangefinder case of the binocular pack and harness set of FIG. 1 with the top flap in open configuration.

FIG. 36 is a front elevation view of the rangefinder case of the binocular pack and harness set of FIG. 1 with the top flap in open configuration.

FIG. 37 is a rear elevation view of the rangefinder case of the binocular pack and harness set of FIG. 1 with the top flap in open configuration.

FIG. 38 is a right side view of the binocular pack and harness set of FIG. 1 with the top flap in open configuration.

FIG. 39 is a left side view of the binocular pack and harness set of FIG. 1 with the top flap in open configuration.

FIG. 40 is a top plan view of the binocular pack and harness set of FIG. 1 with the top flap in open configuration.

FIG. 41 is a bottom plan view of the binocular pack and harness set of FIG. 1 with the top flap in open configuration.

FIG. 42 is a front, top perspective view of a harness of the binocular pack and harness set of FIG. 1.

FIG. 43 is a rear, lower perspective view of the harness of the binocular pack and harness set of FIG. 1.

FIG. 44 is a front elevation view of the harness of the binocular pack and harness set of FIG. 1.

FIG. 45 is a rear elevation view of the harness of the binocular pack and harness set of FIG. 1.

FIG. 46 is a right side view of the harness of the binocular pack and harness set of FIG. 1.

FIG. 47 is a left side view of the harness of the binocular pack and harness set of FIG. 1.

FIG. 48 is a top plan view of the harness of the binocular pack and harness set of FIG. 1.

FIG. 49 is a bottom plan view of the harness of the binocular pack and harness set of FIG. 1.

FIG. 50 is a front, top perspective view of a harness of the binocular pack and harness set of FIG. 1 configured to be worn by a user.

FIG. 51 is a rear, lower perspective view of the harness of the binocular pack and harness set of FIG. 1 configured to be worn by a user.

FIG. 52 is a front elevation view of the harness of the binocular pack and harness set of FIG. 1 configured to be worn by a user.

FIG. 53 is a rear elevation view of the harness of the binocular pack and harness set of FIG. 1 configured to be worn by a user.

FIG. 54 is a right side view of the harness of the binocular pack and harness set of FIG. 1 configured to be worn by a user.

FIG. 55 is a left side view of the harness of the binocular pack and harness set of FIG. 1 configured to be worn by a user.

FIG. 56 is a top plan view of the harness of the binocular pack and harness set of FIG. 1 configured to be worn by a user.

FIG. 57 is a bottom plan view of the harness of the binocular pack and harness set of FIG. 1 configured to be worn by a user; and,

FIG. 58 is a front, top perspective view of a harness of the binocular pack and harness set of FIG. 1 configured to be worn by a user and hold binoculars.

Broken lines shown in the drawings indicate portions of the binocular pack and harness set, including stitching, that form no part of the claimed design.
